DESIGN FOR A SPOON OR SIMILAR ARTICLE

Arthur A. Eisenberg, New York, N. Y., assignor to National Silver Company, New York, N. Y., a corporation of New York

Application July 2, 1937, Serial No. 70,207

Term of patent 14 years

To all whom it may concern:

Be it known that I, Arthur A. Eisenberg, a citizen of the United States, residing at No. 865 West End Avenue, New York, New York, in the county of New York and State of New York, have invented a new, original, and ornamental Design for a Spoon or Similar Article, of which the following is a specification, reference being had to the accompanying drawing, forming part thereof.

I claim:

The ornamental design for a spoon or similar article as shown. ARTHUR A. EISENBERG.
